United States Patent Office

Des. 185,641
Patented July 7, 1959

185,641

LUGGAGE HANDLE

Henry L. Kotkins, Seattle, Wash.

Application December 16, 1958, Serial No. 53,789

Term of patent 14 years

(Cl. D87—2)

Fig. 1 is a perspective view of a luggage handle showing my new design;

Fig. 2 is a side elevational thereof;

Fig. 3 is an end view thereof, and

Fig. 4 is a top plan view of the same.

Fig. 5 is a perspective view thereof on a smaller scale with an article of luggage shown in broken lines for purpose of illustration.

I claim:

The ornamental design for a luggage handle, as shown and described.
